PAINT COLOR DISPLAY CABINET

Myles W. Leep, Jr., Milwaukee, Wis., assignor to Wm. F. Zummach, Inc., Milwaukee, Wis., a corporation of Wisconsin

Filed Sept. 19, 1960, Ser. No. 62,190

Term of patent 7 years

(Cl. D80—11)

FIG. 1 is a front perspective view taken from the top and left end of a paint color display cabinet, showing my new design; and

FIG. 2 is a vertical cross-sectional view thereof taken on line 2—2 of FIG. 1.

The rear and bottom of the cabinet are substantially plain and the right end is a mirror image of the left end shown.

I claim:

The ornamental design for a paint color display cabinet, as shown and described.
